UNITED STATES PATENT OFFICE

105,530

DESIGN FOR A LAMP SHADE

John A. Korengold, Chicago, Ill.

Application April 22, 1937, Serial No. 68,922

Term of patent 7 years

To all whom it may concern:

Be it known that I, John A. Korengold, a citizen of the United States, residing at the city of Chicago, county of Cook, State of Illinois, have invented a new, original, and ornamental Design for a Lamp Shade, of which the following is a specification, reference being made to the accompanying drawing, forming a part thereof, in which Figure 1 is a perspective view, Figure 2 is a side elevational view, and Figure 3 is a front elevational view of a lamp shade embodying my new design.

I claim—

The ornamental design for a lamp shade, substantially as shown.

JOHN A. KORENGOLD.
